PANTOGRAPH ENGRAVING OR LIKE MACHINE

Gene Kapp and Norbert Schimmel, New York,
N. Y., assignors to New Hermes, Inc., New York,
N. Y., a corporation of New York

Application September 24, 1938, Serial No. 231,454

14 Claims. (Cl. 90—13.1)

This invention relates to machines, particularly adapted for engraving, marking or cutting on any suitable objects, designs, indicia or other desired characters of a predetermined scale reproduced from a pattern by means of a pantograph or like mechanical organization.

It is an object of the invention to provide simple, inexpensive and rapidly operable means to perform the aforementioned engraving or like 10 operation.

It is another object of the invention to provide in such a machine means for reproducing the indicia, said means being swingably supported on the pantograph leverage and being preferably 15 movable with respect to the workholder carrying the object to be worked upon.

Still another object of the present invention is to provide means for resiliently urging said reproducing means against the said leverage.

20 A further object of the present invention is to connect the stylus for the indicia and the engraving or like means with respect to the pantograph leverage such that the stylus and said means are swingable in planes perpendicular to that of said 25 leverage.

Still another object of the invention resides in the provision of indicia reproducing means which are guidingly and swingably arranged at the pantograph leverage and which are relatively 30 movable to spring supported clamping means for holding in position the object to be worked upon.

The present invention further contemplates the provision of indicia reproducing means which may be selectively actuated during the operation of 35 the stylus.

A further object of the invention is to provide a horizontally and rotatably movable pantograph leverage whilst both said indicia reproducing means and said clamping means of the workholder are movable substantially in a perpendicular plane and in opposite directions with respect to each other.

A further object of the present invention is to provide adjustable means for varying the size and/or style of the reproduction of the indicia.

Other objects will be in part apparent, and in part pointed out hereinafter.

Accordingly, the invention consists in the features of construction, combination of elements 50 and arrangements of parts, all as will be illustratively set forth in the following description, and the scope of the application of which will be indicated in the appended claims.

In the accompanying drawings, in which is 55 shown one of the various possible embodiments

of the invention, and in which like numerals represent like parts:

Fig. 1 is a top plan view of an engraving device incorporating the invention.

Fig. 2 is a side elevation of the device shown in 5 Fig. 1.

Fig. 3 is a longitudinal sectional view of the needle holding arm and adjacent parts on an enlarged scale.

Figs. 4 to 6 are diagrammatic views, showing 10 different positions of the engraving or like tool with respect to the pantograph leverage and the pivot thereof.

Figs. 7 and 8 are diagrammatic views showing 15 still other positions of the tool with respect to the pantograph leverage and the pivot thereof.

Referring now to the drawings, numeral 10 designates a base upon which the motor 11 is mounted. The motor 11 is provided with a pulley 12 over which is trained preferably a spring belt 20 13, the latter further being trained over pulley 14, fixed to a hollow shaft 15 provided at the arm 16 of the machine. Adjacent the said motor 11, there is located a swingable lever 17 which is pivotally and resiliently attached at one of its 25 ends to a post 18 at 19 and which carries at its other end a shaft 20. This shaft 20 supports two adjacently arranged pulleys 21, 22 over which the said spring belt 13 is guided. This arrangement consequently provides a uniformly tensioned 30 belt-organization; the belt 13 being rotatably guided over pulleys 12—21—14—22 and back to pulley 12 of the motor 11.

On base 10, there is fixedly arranged a vertical post 23 on which is rotatably mounted the sleeve 24. Attached to sleeve 24 is a horizontal arm 25. In spaced apart parallel relation with arm 25 is another arm or lever 26, there being a strap 27 pivotally connecting both of said arms 25, 26, the said strap 27 being detachably secured thereto by 40 means of threaded elements 28. Pivotally connected at the free ends 29 and 30 of the respective arms 25, 26 by means of screws 36 is a second strap 31 to which is pivotally linked the lever 32. This pivotal effect is brought about by means of the pins 33, 33'. At the free end of lever 32, there is provided the upper end of the stylus 35. In the path of the pointed end 37 of the stylus 35 is a support 38 upon which may be adjustably and 50 removably positioned a plate, strip or sheet 39 carrying the indicia 40 to be reproduced. Support 38 is arranged on base 10 in any suitable manner. Slidably arranged on the support 38 are clamping members 41 with engaging members 55

42 for holding the indicia carrying plate 39 in desired position.

5 Arm 43 is pivotally connected for vertical swinging movement at 44 to arm 16. The aforementioned arms 25, 26 are detachably secured to arm 43 by means of the screws 45, 46. One end of arm 43 carries a guide pin 47 received in the upper coils of a spring 48, the lower portion of said spring being inserted in a socket 49 formed 10 within the upset portion 50 of arm 16. The other end of arm 43 is arranged to ride between stops 51, 52 by a tongue and groove arrangement 53, 53' provided respectively in the raised hollow or sleeved portion 54 of arm 16 and on arm 43. 15 Within portion 54, there is a bushing 55 having an extended threaded end 56 threadedly receiving a cap 57 thereon. Within bushing 55 are thrust bearings 58 which abut against the hollow shaft 15 and also against the wall of bushing 55. Bearings 58 are maintained in position by shoulders 59 of shaft 15. Partially within and projecting from bushing 55 is the hollow end piece 60 for housing the lower extension 61 of shaft 15 and also the lower end of engraving needle 62, the 20 latter passing through and protruding from the said hollow shaft 15. Needle 62 has a head 63 and a threaded portion 64 which threadedly engages the extension 65 of the shaft 15, the extension 65 being externally threaded for engagement of pulley 14. End piece 60 has a shoulder 66 which abuts against the bushing 55. Bushing 55 may be held in position by a set screw 67 located in the recess 68 of the sleeved portion 54 of arm 16. Extending from portion 54 is a pin 35 69 carrying at its upper end a knob 70 to be contacted by a finger or thumb of the hand of the operator for depressing said arm 16. Needle 62 is removed by unthreading the same at 64 from the hollow shaft 15. To dismantle for repair or 40 other purposes pulley 14 is unthreaded from shaft 15. Cap 57 may then be removed from bushing 55 so as to enable the withdrawal of hollow shaft 15 when desired.

On base 10 and within the reach of the needle 45 62, there is provided a workholder 71. Workholder 71 is substantially comprised of U-shaped stands 72, each having a pair of posts 72' and the clamping device 73. Clamping device 73 is resiliently supported by coil springs 75 and guided 50 by vertical pins 76 slidable in sleeves 76' of said base 10. Clamping device 73 provides a swingable lever 77, which is pivoted at 74 and connects with preferably grooved bars 78, the said bars being urged upwardly by the action of said 55 springs 75. Bridged across opposite posts 72' of the stands 72 are the connecting rods 79 forming slideways for the transverse members 80. These members 80 may be adjusted to any convenient position on said rods 79. It is to be observed, that the transverse members are located 60 above and spaced from the bars 78 to enable the clamping therebetween of an article, such as a vanity case 81 made of metal with or without an enamel surface, indicated in dotted lines, for the engraving or like working operation.

In order to perform the engraving or like operation, the interchangeable indicia or indicia parts are placed on support 38 and positioned on 40 by means of screws 41 and plates 42.

70 Motor 11 is then switched on by means of switch S.

The article to be worked upon is clamped in position between the cross-members 80 and clamping bars 73. This is effected by depressing 75 knob 90 of lever 77. The lever 77 has a pin 91

on either side, which pin rides in a slot 92 formed in each depending lug 93 on each bar 78. Depressing lever 77 causes the pins 76 to lower within guiding sleeves 76' against the action of springs 75. After the article to be worked upon is placed in position on bars 78, lever 77 is released and the article is maintained in clamped position presenting the surface to be worked upon.

The stylus 35 is gripped by the hand of the operator, which may be guided in suitable manner. The tool holder arm 16 is moved downwardly by depressing on knob 70 until the point of the tool 62 bears against the article to be worked upon. Tool 62, as heretofore stated, is rotated at high speed and is made to follow by means of the pantograph leverage the movement of the stylus 35. Uniform depth of the engraved or worked portion on the article is assured by the particular arrangement, heretofore described, and including the end piece 60, which forms an abutment against the surface of the article while the tool is in cutting or like operation.

The size and/or style of the indicia or parts thereof may be varied in the following manner:

A plurality of perforations 82, 84, 83, 85 and 86 are provided in lever 43. Arm 25, which is horizontally movable about pivot post 23, is also provided with a plurality of apertures 87, 88 and 89. Corresponding apertures 87', 88' and 89' are provided on lever arm 26.

Referring now to the diagrams, shown in Figs. 4 to 6, in order to obtain a true reproduction of the indicia to be copied, the distance R between pivot 23 and the articulated point 83 must be equal to the distance R between the latter point 83 and the axial center of tool 63. Figs. 4, 5 and 6 show this relation in various regular degrees for obtaining different sizes of reproduction, i. e. of the letter B, shown in script form. The distance R of Fig. 4 is reduced in Fig. 5 to the distance W and further in Fig. 6 to the distance X, the lever arm 43 being thus attachable to respective pantograph levers 25, 26 by means of screws 45, 46 with varying distances R, W, X from pivot point 23.

In Figs. 7 and 8 the relative arrangement between the articulated point 84 and the axial tool center 63 is such that the distance Y is less than the distance between the point 83 and pivot 23 (illustrated in Fig. 4), thus obtaining a reproduction of the letter B in a different style, i. e. in a more oblique form. For instance, when the arrangement, shown in Fig. 4 is provided, the tool accurately reproduces the outline followed by the stylus of the indicia or signature to be copied, and when the arrangements, shown in Figs. 7 and 8 are provided, the said outline is reproduced in different styles and sizes respectively. It is to be noted, that in the arrangements shown in Figs. 4, 7 and 8, the height of the letter B is the same. This is, because the distance between pivot 23 and the respective points 83, 84, 82 remains the same. The width of the letter B, however, as well as its slant (shown in Figs. 7 and 8) differs, because of the differing leverage of the pantograph due to the variation in distances between the axis of tool 63 and the respective fulcrum points 84 and 82 on lever 25.

A plurality of different styles and/or sizes may thus be obtained by changing the relation between the fixed and fulcrumed points.

The direction of the reproduction of the indicia with respect to the article surface in which it is formed may be changed by the provision of

means to swing and adjust the member carrying the indicia with respect to the stylus.

Although we have described the improvements of the invention in a certain form, we do not desire to be limited to such details since many changes and modifications may be made without departing from the scope of this invention.

Having thus described our invention, what is claimed as new and desired to secure by Letters Patent is:

1. An engraving or copying machine for reproducing indicia and having a pantograph leverage with a stylus for following said indicia; comprising a work holder, and means for reproducing said indicia, said work holder including clamping means resiliently supported thereon, said clamping means and said reproducing means being relatively movable in a perpendicular plane toward each other.

2. An engraving or copying machine for reproducing indicia and having a pantograph leverage with a stylus for following said indicia; comprising a work holder, a lever, and means for reproducing said indicia, said reproducing means being connected to said lever, said lever being resiliently linked to said leverage for relative movement of said means toward said work holder.

3. An engraving or copying machine for reproducing indicia and having a pantograph leverage with a stylus for following said indicia; comprising a work holder, a lever, and means for reproducing said indicia, said reproducing means being supported by said lever, said lever being resiliently and swingably connected to said leverage for relative movement of said means toward said work holder.

4. An engraving or copying machine for reproducing indicia and having a pantograph leverage with a stylus for following said indicia; comprising a work holder, a lever, means for reproducing said indicia, said reproducing means being supported by said lever, said lever being provided with a slideway for guidingly receiving therein an end of a portion of said leverage and a pivot swingably connecting said reproducing means through said lever to said portion, and spring means at the free ends of said lever and said portion to resiliently engage said lever and said portion, whereby a relative movement of said reproducing means toward said work holder is obtained.

5. An engraving or copying machine for reproducing indicia and having a pantograph leverage with a stylus for following said indicia; comprising a workholder, a lever, means for reproducing said indicia, said reproducing means being supported by said lever, said lever having a slideway for guidingly receiving therein an end of a portion of said leverage, and a pivot for swingably connecting said reproducing means through said lever to said portion, and spring means at the free ends of said lever and said portion to resiliently engage said lever and said portion, said workholder including clamping means resiliently supported thereat, whereby a relative movement of said reproducing means toward said workholder in a substantially perpendicular plane is obtained.

6. An engraving or copying machine for reproducing indicia and having a pantograph leverage with a stylus for following said indicia; comprising a workholder, an arm, means for reproducing said indicia, said reproducing means being supported by said arm, said arm having a

slideway for guidingly receiving therein an end of a portion of said leverage, and a pivot for swingably connecting said reproducing means through said arm to said portion, and resilient means between said arm and said portion, said workholder including clamping means resiliently supported thereat, whereby a relative movement of said reproducing means toward said workholder in a substantially perpendicular plane and in opposite direction is obtained.

7. An engraving or copying machine for reproducing indicia and having a pantograph leverage with a stylus for following said indicia; comprising a workholder, clamping means resiliently connected to said workholder and movable in a substantially vertical plane, an arm, means for reproducing said indicia, said reproducing means being connected with said arm, said arm being swingably and resiliently supported on a portion of said leverage, a slideway on said arm for guidingly receiving therein an end of said portion of said leverage, and stops relatively positioned with respect to said slideway and said end of said portion for limiting the swinging movement of said arm, whereby a relative movement of said reproducing means toward said workholder in a substantially perpendicular plane and in opposite direction is obtained.

8. An engraving or copying machine for reproducing indicia and having a pantograph leverage with a stylus for following said indicia; comprising a workholder, clamping means resiliently connected to said workholder and movable in a substantially vertical plane, an arm, means for reproducing said indicia, said reproducing means being connected with said arm, said arm being swingably and resiliently supported on a portion of said leverage, a slideway on said arm for guidingly receiving therein an end of said portion of said leverage, means for relatively adjusting said portion of said leverage thereat, and stops relatively positioned with respect to said slideway and said end of said portion for receiving the swinging movement of said arm, whereby a relative movement of said reproducing means toward said workholder in a substantially perpendicular plane and in opposite direction is obtained.

9. An engraving or copying machine for reproducing indicia and having a pantograph mechanism with a stylus for following said indicia; comprising a workholder, a lever forming part of said mechanism, an arm for carrying means for reproducing said indicia, said lever and said arm being linked together and maintained in spaced apart relation, and adjustable means connecting said lever to said mechanism, said lever with said mechanism being journaled on a pivot for horizontal movement, said arm and said reproducing means being swingably movable in a substantially vertical plane toward and from said workholder.

10. An engraving or copying machine for reproducing indicia and having a pantograph mechanism with a stylus for following said indicia; comprising a base, a workholder on said base, said workholder including a portion cooperable therewith and resiliently connected to said base, said portion being substantially movable in a vertical plane, a lever forming part of said mechanism, an arm for carrying means for reproducing said indicia carried by said arm, said lever and said arm being linked together and resiliently maintained in spaced apart relation, and adjustable means connecting said lever to said mechanism, said lever with said mechanism being journaled on a

pivot for horizontal movement, said arm and said reproducing means being swingably movable in a substantially vertical plane toward and from said workholder.

- 5 11. An engraving or copying machine for reproducing indicia and having a pantograph leverage with a stylus for following said indicia; comprising a workholder, and means for reproducing said indicia, said workholder including clamping means resiliently and guidingly arranged with respect to the remainder of said workholder, said clamping means and said reproducing means being relatively movable in a substantially perpendicular plane toward each other.
- 10 12. An engraving or copying machine for reproducing indicia and having a pantograph leverage with a stylus for following said indicia; comprising a base, a workholder on said base, and an engraving tool for reproducing said indicia connected to said leverage, said workholder including clamping means provided with a lever projecting therefrom and beyond the remainder of said workholder, said clamping means being resiliently connected to said base and being guidingly movable with respect to the remainder of said workholder and relatively to said tool, said lever being operable from without said remainder of said workholder.

13. An engraving or copying machine for reproducing indicia and having a pantograph leverage with a stylus for following said indicia; comprising a workholder, and an engraving tool for reproducing said indicia connected to said leverage, said tool being resiliently held in one position and swingable in an arcuate path toward said workholder into another position, said workholder including clamping means, said clamping means being resiliently and guidingly disposed relatively 10 to the remainder of said workholder.

14. An engraving or copying machine for reproducing indicia and having a pantograph leverage with a stylus for following said indicia; comprising a workholder, and an engraving tool for 15 reproducing said indicia connected to said leverage, said tool being resiliently held in one position and being guidingly swingable in an arcuate path toward said workholder into another position, said workholder including clamping means, said 20 clamping means being resiliently and guidingly disposed adjacent the remainder of said workholder and being movable relatively to the latter and said tool.
